UNITED STATES PATENT OFFICE.

FRANK ZALESKI, OF SOMERVILLE, MASSACHUSETTS, ASSIGNOR TO THE REECE
BUTTON HOLE MACHINE COMPANY, OF BOSTON, MASSACHUSETTS, A COR-
PORATION OF MAINE.

BUTTONHOLE-SEWING MACHINE.

1,152,465.

Specification of Letters Patent. Patented Sept. 7, 1915.

Application filed September 29, 1914. Serial No. 864,187.

To all whom it may concern:

Be it known that I, FRANK ZALESKI, a subject of the Emperor of Germany, residing at Somerville, county of Middlesex, State of 5 Massachusetts, have invented an Improvement in Buttonhole-Sewing Machines, of which the following description, in connection with the accompanying drawing, is a specification, like characters on the drawing representing like parts.

This invention relates to buttonhole-sewing machines of that type which comprise an upper thread mechanism and an under thread mechanism that coöperate to produce the edge stitches on a buttonhole, and the object of the invention is to provide means for clamping and holding the under thread after said thread has been severed upon the completion of the buttonhole.

20 In buttonhole sewing machines that are not provided with my improvements it is necessary for the operator upon completing the buttonhole to draw out a length of both the upper and the under thread and then 25 to hold the ends of both threads in his fingers while starting the fresh buttonhole in order that the first stitches of the buttonhole may be properly formed. With my improvement this manipulation of the threads 30 on the part of the operator is not necessary as the first stitches of the new buttonhole are properly formed by reason of the improvements herein described. My improvements, therefore, enable an operator to run 35 a machine at a faster speed because he can shift from one buttonhole to another without necessitating any pause for the manipulation of the threads.

In order to illustrate my invention and 40 give a proper understanding thereof, I have shown it as it would be applied to a buttonhole sewing machine of the type commonly known to the trade as the "Reece" machine, such a machine being illustrated in any one 45 of the following United States Letters Patent: No. 494,280, March 28, 1893; No. 498,216, May 23, 1893; No. 655,637, August 7, 1900.

50 Sewing machines of the above type comprise a clamp frame in which the work is clamped and a so-called "stitch frame" carrying an upper thread mechanism (usually in the form of a straight eye-pointed needle) for manipulating the upper thread, and an

under thread mechanism (or as it is sometimes called a complementary stitch-forming mechanism) for manipulating the under thread, said under thread mechanism including a curved eye-pointed needle carrying the under thread and which operates through a 60 throat-plate and coöperates with the upper needle to concatenate the edge stitches of a buttonhole. In sewing machines of this type the stitch frame and the clamp frame are mounted for movement relative to each 65 other, and means are provided whereby when the machine is first started the stitch frame and clamp frame have first a relative movement by which the work clamped in the clamp frame is brought into proper position to have the buttonhole stitched by the upper and under thread mechanisms, and then the stitch-forming mechanism is set in 70 operation and said stitch frame and clamp frame have another relative movement to cause said stitch-forming mechanism to 75 stitch around the edge of the buttonhole, after which the stitch-forming mechanism ceases to operate and said two frames have another relative movement to return the 80 parts to their initial position.

My improvements comprise means associated with the under thread mechanism for clamping the under thread at the completion of the buttonhole, and for holding said 85 thread clamped until the stitching mechanism has been started to form stitches on the next succeeding buttonhole, at which time the end of the under thread is released, and also comprise means associated with 90 the upper thread mechanism to draw out from said upper thread mechanism a sufficient length of upper thread at the completion of the buttonhole to provide for the formation of the first stitches of the second 95 buttonhole.

In order to give an understanding of the invention I have illustrated in the drawings a selected embodiment thereof which will now be described, after which the novel features of the invention will be pointed out 100 in the appended claims.

Figure 1 is a side view of a portion of a so-called "Reece" buttonhole machine having my improvements applied thereto; Fig. 105 2 is a plan view of a portion of the machine with part of the stitch frame and clamp frame broken out; Figs. 3, 4 and 5 are dia-

grammatic views showing the movements of the throat-plate during the stitching operation; Fig. 6 is a section on the line 6—6, Fig. 2; Fig. 7 is a bottom plan view of the 5 clamp plate; Fig. 8 is a fragmentary view of the thread-cutter-actuating mechanism looking in the direction of the arrow, Fig. 2; Fig. 9 is a plan view of the throat-plate showing the thread clamp open; Fig. 10 is 10 a similar view showing the thread clamp closed and clamping the under thread; Fig. 11 is a section on the line 11—11, Fig. 9; Fig. 12 is a side view of Fig. 9 looking toward the left.

15 The drawings show the sewing machine with the parts in the position they assume when the machine has been brought to rest at the time that a buttonhole has been completed. A complete sewing machine is not 20 herein illustrated, but only the parts thereof which are necessary to illustrate my invention.

1 indicates the base frame of the machine on which is mounted the clamp plates 2 and 25 3 of the clamp frame, said clamp frame also including the clamping member 4 which is normally separated from the clamp plates but is adapted to be moved down against them to clamp the work in position for the 30 stitching operation. The clamp frame is shown as provided with an elongated opening 6 through which the stitching mechanism operates to form the edge stitches to the buttonhole.

35 5 indicates a part of the so-called stitch frame which carries the upper and under thread mechanism. The upper thread mechanism is in the form of a straight eye-pointed needle 7 carried by the usual needle bar 8 which in addition to its reciprocating movement is given a rotary movement by the 40 gears 9 as the stitches are formed around the ends of the buttonhole, as usual in sewing machines of this type. The stitch frame 5 also carries an under thread mechanism shown generally at 10 and which has as 45 part thereof a throat-plate 11 provided with an opening 12 and an under thread needle 13 which operates through the opening 12, said needle usually being curved, as 50 shown in Fig. 12. This under thread mechanism is also rotatably mounted in the stitch frame so that it rotates about its axis perpendicular to the work in rounding the ends 55 of the buttonholes, as usual in sewing machines of this type. The stitch frame and the clamp frame have a movement relative to each other in the formation of the buttonhole, and during such movement the under 60 and upper thread mechanisms have a rotary movement about their axes to provide for stitching around the ends of the buttonhole. These relative movements are illustrated 65 diagrammatically in Figs. 3, 4 and 5 wherein the circles represent the position

of the throat-plate, and the elongated outline 14 shows the position of the buttonhole to be stitched, this buttonhole being situated directly over the opening 6 in the clamp frame, it being understood that the work ^w in which the buttonhole is formed is firmly held in position by the work clamp 4. The arrows in the circle of the diagrams show the relative positions of the same part of the throat-plate, and thus illustrate how the ⁷⁰ throat-plate turns as it has a bodily movement. The position of the throat-plate when the machine is at rest before the stitching operation begins is shown at *a*. When the machine is first set in operation the ⁷⁵ stitch frame and clamp frame have a relative movement to bring the throat-plate nearer to the opening 6 in the clamp frame and then to carry the throat-plate laterally or longitudinally of said opening 6 through ⁸⁰ the various dotted line positions Fig. 3 into the full line position marked *b*, and during this relative movement the under thread mechanism and throat-plate are turned into the various positions indicated by the arrows ⁸⁵ *b*, *c*, *d*, *e*, *f*, *g*. When the parts have been brought into the position indicated by the outline *b*, Figs. 3 and 4, the stitching operation begins, and then the stitch frame has a lateral movement and at the same time the ⁹⁰ upper and under thread mechanisms rotate about their axes, thus carrying the throat-plate through the successive positions indicated by *b*, *i*, *j*, *k*, *l*, *m*, *n*, *o*, *p*, Fig. 4, the buttonhole being completed when the parts ⁹⁵ reach the position *p*. During this time the stitch-forming mechanism has been carried completely around the buttonhole. When the parts reach the position of the circle *p* in Figs. 4 and 5, the stitching ceases, and ¹⁰⁰ thereafter the stitch frame and clamp frame have another relative movement to return the parts to their original position indicated by the circle *s*, Fig. 5, the throat-plate being carried through the successive positions *q*, *r*, ¹⁰⁵ *s* at this time. Inasmuch as this type of sewing machine is well known, further description of the operation is not necessary.

The mechanism herein shown has incorporated therein a thread-cutting device ¹¹⁰ shown as a cutting blade 15 operating beneath the clamp plate and co-operating with the cutting block 16 carried by the clamp frame, all as shown in my co-pending application, Ser. No. 842,278, filed June 1, 1914. ¹¹⁵ This thread-cutting blade is mounted on a lever 17 pivoted at 18 to the clamp plate 2, and it is actuated during the movement of the parts from the position *p* to the position *s*, Fig. 5, at the completion of the ¹²⁰ buttonhole by mechanism similar to that illustrated in said co-pending application, and which comprises a finger 19 carried by the under thread mechanism and adapted to engage an actuator 20 that is pivotally con- ¹²⁵

nected at 21 to an arm 22 pivoted at 23 to the clamp frame 2 and connected by the spring 24 with the lever 17. The parts are so arranged that during the final relative 5 movement of the clamp frame and stitch frame the finger 19 engages the actuator 20, as shown in full lines Fig. 7, thereby swinging the lever 17 to bring the blade 15 against the cutting block 16 and thereby cutting 10 the under thread 99 and the loop of upper thread that is held by the looper.

One feature of my present invention relates to means for clamping the under thread just prior to its being severed, as 15 above described, which clamping means holds the severed end of the under thread firmly until after the stitching mechanism is set in operation to form the next succeeding buttonhole, at which time the clamping 20 mechanism is actuated to release the end of the thread. This clamping mechanism is shown as associated with the throat-plate and comprises a rotary clamping ring 25 mounted on the throat-plate for turning 25 movement and provided with a clamping shoulder 26 which coöperates with a clamping shoulder 27 formed on the throat-plate. This clamping ring 25 is illustrated as provided with a notch or recess 28 through 30 which the under thread normally passes, and one wall 26 of which constitutes the thread-clamping edge. This clamping ring 25 may be mounted on the throat-plate in various ways without departing from the 35 invention. As herein shown, it is supported on the body portion of the throat-plate and is held in position thereon by the top portion 29 which partially overlies the clamping ring 25. During the stitching operation 40 the clamping ring has the position shown in Fig. 9 and the under thread can pass freely through the opening 28 therein. After the stitching operation is completed and during the relative movement of the 45 stitch frame and clamp frame to bring the throat-plate from the position shown at *p*, Fig. 5, to that shown at *s*, the clamping member 25 is turned into the position shown in Fig. 10 thereby to clamp the under thread 50 between the shoulders 27 and 26, and just after this occurs the cutting blade 15 is actuated to sever the under thread. The under thread remains thus clamped until the stitching operation of the next buttonhole 55 is commenced, that is, until the throat-plate has moved from the position *a*, Fig. 3, to that shown at *h*, Figs. 3 and 4, and during the movement of the throat-plate from the position *h* to the position *i* Fig. 4 (that is, 60 just after the stitching operation has begun) the clamping member 25 is moved back into the position shown in Fig. 9, thereby to release the under thread. To accomplish these 65 two movements of the clamping member 25 the latter is provided with two projections

30 and 31 and the clamp frame is also provided with two projections 32, 33 which are situated to engage the projections 30 and 31 at the proper time during the relative movements of the clamp frame and stitch frame. The projection 32 coöperates with the projection 30 to clamp the thread, and the projection 31 coöperates with the projection 33 to unclamp the thread. During the movement of the throat-plate from the position shown at *r* to *s*, Fig. 5, that is, just before the parts come to rest upon the completion of a buttonhole, the projection 30 on the clamping member meets a projection 32 on the clamp plate, thereby turning the clamping member from the position shown in Fig. 9 to that shown in Fig. 10, and clamping the thread. The clamping member will remain in this position until the machine is started again and the throat-plate has been carried into the position shown at *h*, Fig. 4, and while it is moving from position *h* to position *i*, Fig. 4, the projection 31 meets the projection 33 and thereby turns the clamping member back 75 again to the position shown in Fig. 9.

The projection 33 is preferably yieldingly mounted and the projection 31 is provided with a curved rear face, the purpose of this being so that when the throat-plate is moving from the position *f* to the position *h*, Fig. 3, the projection 31 will wipe by the projection 33, the latter yielding backwardly about its pivot 34. When the throat-plate, however, is moving from the position *h* to the position *i*, the projection 33 will operatively engage the projection 31 to unclamp the under thread. I have shown the projection 33 as acted on by a spring 35 which normally holds it in operative position but permits it to yield. 90

I have herein shown a device for drawing out a suitable length of upper thread upon the completion of the stitching operation so that when the machine is started up again 100 to stitch a fresh buttonhole it will not be necessary for the operator to perform such operation. The means illustrated for this purpose are as follows: Mounted on the stitch frame 5 is a bracket 38 upon which is pivotally mounted a forked member 39 over the arms of which the upper thread 36 passes. This forked member 39 is mounted on a shaft 40 pivoted in the bracket 38, and the shaft has fast thereto an arm 41 110 which is connected by a link 42 with an arm 43 fast on a rock-shaft 44 mounted in bearings 45 carried by the stitch frame. This rock-shaft 44 has also fast therewith another arm 46, the lower end of which is bent 115 laterally, as at 47, and is held in a groove formed in a block 48 fast on the frame 1. With this construction the forward and backward movement of the stitch frame 5 will swing the forked member 39 from the 120 125 130

full to the dotted line position Fig. 1. The dotted line position represents the position of the stitch frame while the stitching operation is being performed and during this time the forked member 39 is not acting on the upper thread 36 as it is occupying the dotted line position Fig. 1. When the stitch frame moves forward into the full line position Fig. 1, then the member 39 is turned so as to act on the thread 36, as shown in Fig. 1, to place some slack therein. During this operation the tension 37 is released automatically so that this movement of the member 39 draws thread from the thread supply. The releasing of the tension is accomplished by the usual tension-releasing member 50 mounted in bearings 51 in a bracket 52 secured to the stitch frame and adapted at its lower end to engage the block 53 secured to the frame 1 and having the two surfaces 54 and 55 at different elevations and connected by the inclined surface 56. When the parts move from the dotted to the full line position Fig. 1, the inclined surface 56 raises the member 50, as will be obvious. The upper end of the member 50 is connected to a lever or arm 57 pivoted to the stitch frame at 58 and having rigid therewith an arm or finger 59 which engages the stem 60 of the tension 37, so that the swinging movement of the member 57 due to the raising of the member 50 releases the tension on the thread.

The work clamp 4 is provided with a cross-bar 61 over which the thread 36 passes, as shown in Figs. 1 and 6, and when the parts move from the dotted to the full line position Fig. 1 at the completion of the stitching operation, the engagement of this bar 61 with the thread draws backwardly on the latter, and this co-operating with the action of the member 39 draws off from the thread supply, and through the tension 37, a sufficient length of upper thread so that when the stitching operation begins again there will be enough thread projecting beyond the needle 7 to provide for properly making the first stitch of the new buttonhole without the necessity of the operator holding the end of the upper thread.

The operation of the bar 61 results in drawing the upper thread through the eye of the needle, as is clearly evident from Fig. 1. When, therefore, the upper thread is severed and the needle makes its first penetrating movement in the formation of the first stitch of the next succeeding buttonhole, there will be a sufficient length of thread projecting through the eye of the needle so that when the needle has made its full downward thrust the end of the thread will still be held in the work *w*. The friction of the cloth or work on the end of the upper thread is sufficient to hold it while the first stitches are being formed so that the

first stitch will be accurately formed and tightly set without any attention on the part of the operator.

By means of the above construction both the upper and under thread are taken care of automatically so that upon completion of a buttonhole the operator can shift the work into position to have a new buttonhole stitched and can set the machine in operation stitching the new buttonhole without paying any attention to the upper and under thread.

I claim:

1. In a buttonhole sewing machine, the combination with upper and under thread mechanism which are mounted for turning movement to effect the stitching around the end of a buttonhole, of under-thread-gripping mechanism mounted to turn with the under thread mechanism, and means to operate said gripping mechanism first to grip the under thread upon the completion of a buttonhole and then to release the under thread after the commencement of the stitching operation on the next buttonhole. 90

2. In a buttonhole sewing machine, the combination with a clamp frame, of a stitch frame having upper and under thread mechanism which are mounted thereon for turning movement to effect the stitching around the end of a buttonhole, said frames being capable of movement relative to each other, and means mounted to turn with the under thread mechanism and rendered operative by such relative movement upon the completion of a buttonhole to grip the under thread and subsequently to release the under thread after the commencement of the stitching operation on the next buttonhole. 100

3. In a buttonhole sewing machine, the combination with a clamp frame, of a stitch frame having upper and under thread mechanism, said frames being capable of movement relative to each other, a thread-clamping member provided with two projections, and means carried by the clamp frame for engaging said projections successively at the completion of a buttonhole and at the commencement of the stitching operations on the next buttonhole thereby to clamp and then unclamp the under thread. 110

4. In a buttonhole sewing machine, the combination with a clamp frame, of a stitch frame having upper and under thread mechanism, said frames being capable of movement relative to each other, a thread-clamping member mounted for turning movement on the under thread mechanism and provided with projections, and means carried by the clamp frame for engaging said projections alternately thereby to clamp the under thread at the end of the stitching operation on a buttonhole and to unclamp said thread at the beginning of the stitching operation on the next buttonhole. 120 125 130

5. In a buttonhole sewing machine, the combination with an under thread mechanism mounted for turning movement to effect the stitching around the end of a buttonhole, of an under thread-gripping member supported to turn with said under thread mechanism, and means to cause said gripping member to grip the under thread upon the completion of a buttonhole.
- 10 6. In a buttonhole sewing machine, the combination with a rotative under thread mechanism having a throat-plate, of an under thread-gripping member mounted on said throat-plate, and means to operate said gripping member to grip the under thread upon the completion of a buttonhole.
- 15 7. In a buttonhole sewing machine, the combination with work-holding means, of an under thread mechanism capable of turning about an axis perpendicular to the work and having a throat-plate provided with a gripping edge, of a thread-gripping member carried by said throat-plate and having a coöperating thread-gripping edge, and means to operate said gripping member to grip the under thread upon completion of the buttonhole.
- 20 8. In a buttonhole sewing machine, the combination with work-holding means, of an under thread mechanism capable of turning about an axis perpendicular to the work and provided with a throat-plate having a thread-clamping edge, of a clamping member rotatable on said throat-plate and provided with a coöperating clamping edge, means to actuate said clamping member to clamp the under thread between said edges upon the completion of a buttonhole.
- 25 9. In a buttonhole sewing machine, the combination with a stitch frame having upper and under thread mechanism capable of turning movement to effect the stitching around the end of a buttonhole, of a clamp frame having provision for clamping the work, said frames being capable of movement relative to each other, a device for gripping the under thread, said device being carried by the under thread mechanism, and means on the clamp frame coöperating with said gripping means to render the latter operative during the relative movement of the stitch frame and clamp frame.
- 30 10. In a buttonhole sewing machine, the combination with a clamp frame having work-clamping means, of a stitch frame carrying upper thread mechanism and under thread mechanism, said under thread mechanism being supported for turning move-
- ment about an axis perpendicular to the work, said frames having a movement relative to each other, and means carried by the under thread mechanism and rendered operative by such relative movement to clamp the under thread upon the completion of a buttonhole.
- 35 11. In a buttonhole sewing machine, the combination with a clamp frame having work-clamping means, of a stitch frame having upper thread mechanism and under thread mechanism capable of turning about an axis perpendicular to the work, said frames having a movement relative to each other, and a thread-clamping member carried by the under thread mechanism and rendered operative by the relative movement of said frames to clamp the under thread upon the completion of a buttonhole and to release the clamp thread after the commencement of the stitching operation on the next buttonhole.
- 40 12. In a buttonhole sewing machine, the combination with a clamp frame having work-clamping means, of a stitch frame having upper thread mechanism and an under thread mechanism supported to be turned about an axis perpendicular to the work, said under thread mechanism including a throat-plate, an under-thread-clamping member mounted on said throat-plate, and means to actuate said clamping member by the relative movement of the frames to clamp the under thread at the end of the stitching operation.
- 45 13. In a buttonhole sewing machine, the combination with a clamp frame having work-clamping means, of a stitch frame having upper thread mechanism and an under thread mechanism supported to be turned about an axis perpendicular to the work, said under thread mechanism including a throat-plate, an under-thread-clamping member mounted on said throat-plate, and means to actuate said clamping member by the relative movement of the frames to clamp the under thread at the end of the stitching operation and to release said thread at the beginning of the stitching operation on the next buttonhole.

In testimony whereof, I have signed my name to this specification, in the presence of two subscribing witnesses.

FRANK ZALESKI.
